UNITED STATES PATENT OFFICE.

WILLIAM J. SHERIFF, OF ALLEGHENY, PENNSYLVANIA.

INJECTOR.

SPECIFICATION forming part of Letters Patent No. 337,877, dated March 16, 1886.

Application filed September 26, 1885. Serial No. 178,307. (Model.)

To all whom it may concern:

Be it known that I, WILLIAM J. SHERIFF, of Allegheny city, in the county of Allegheny and State of Pennsylvania, have invented a new and useful Improvement in Injectors; and I do hereby declare the following to be a full, clear, and exact description of the invention, such as will enable others skilled in the art to which it pertains to make and use the same, reference being had to the accompanying drawings, which form part of this specification, in which—

Figure 1 is a longitudinal sectional view of my improved injector. Fig. 2 is side elevation of the same. Fig. 3 is a front elevation of a modification.

In the drawings, *a* represents the shell, of suitable size and form of construction, and divided into three integrally-formed compartments, *b' b' b²*, by diaphragms *c' c' c²*.

In the diaphragm or partition-wall *c* is formed a valve-seat, *d*, having a valve, *d'*, working therein, attached to a stem, *d²*, and secured to the end of a lever, *e*, for operating the same.

Communicating with and rigidly attached by screw-threads to the partition of the chamber *b'* is a large nozzle, *f*, and small steam-jet pipe, *f'*. Above this nozzle *f* and jet-pipe *f'*, and at right angles thereto, is placed a similar nozzle, *g*, and jet-pipe *g'*, attached to the walls *c' c²* of the chamber *b²*, which chamber *b²* is in communication with a supply-pipe, *h*, while the chamber *b'* below is provided with an exit-pipe, *h'*.

At the top of the shell *a* is placed a steam-pipe, *h²*, communicating with a port, *i*, formed in the side of the shell *a*, in which, and communicating with the chamber *b'* by means of the nozzle *f'*, is a valve, *i'*, operated by the lever *e*. This lever *e* is fulcrumed between the valves *i'* and *d'* in such a manner that when one of the valves, *d'*, is closed the other, *i'*, is open.

The lifting tubes or nozzles *g g'* may be readily detached through the opening *h²*, used for the admission of steam, while the forcing-tubes *f f'* in the chamber *b'* below may in the same manner be detached through the opening *h²* of the exit-pipe.

The operation of my improved device is as follows: To start the injector, the valve *i'* is closed and the valve *d'* is opened by depressing the lever *e*, and steam, being admitted through the opening *h²*, passes through the nozzles *g g'*, producing a vacuum or partial vacuum in the chamber *b²*, and raising the water through the pipe *h* and chamber *b²*, and discharging it from the head *g* into the chamber *b'*, whence it passes through the valve *d'* to the waste or leakage pipe *k*. When the current is fully established, the lever *e* is raised, which closes the valve *d'* and opens the valve *i'*. The steam then passes from the port *i* through the valve *i'* and nozzle *f'*, as well as through the nozzle *g*, and, acting upon the water in the head *g*, induces a current from the chamber *b'*, and drives it through the head *f*, chamber *b'*, and discharge-pipe *h²* into the boiler.

The construction and operation just described have the advantage of the lifting-tubes *g g'* and forcing-tubes *f f'* at right angles to each other, which is considered a better position than if parallel to each other, being operated in a more easy and simple manner.

Each tube and nozzle may be detached and replaced without disturbing the other.

Fig. 3 shows a construction similar to Figs. 1 and 2, the internal parts being the same, while the outside arrangements differ in having globe-valves with separate means for operating the same, the said valves being articles of general merchandise, and procured at any machine-shop.

Having thus described my invention, what I claim, and desire to secure by Letters Patent, is—

1. In an injector, the combination, with a shell, as *a*, having integrally-formed compartments, as *b' b' b²*, and a steam-port, as *i*, of removable vertical lifting-tubes, as *g g'*, a supply-pipe, as *h*, a steam-inlet valve, as *i'*, horizontal forcing-tubes, as *f f'*, a waste-watter discharge-valve, as *d'*, and mechanism, substantially as described, for operating the valves, as and for the purpose set forth.

2. In an injector, the combination, with a shell having an integrally-formed steam-port *h²*

and a waste-water chamber, each provided with a valve-seat, of valves, as *i'* and *d'*, connected with an actuating-lever fulcrumed between said valves, so that when one valve is 5 open the other will be closed, substantially as described, and for the purpose stated.

In testimony whereof I have hereunto set

my hand this 9th day of September, A. D. 1885.

WILLIAM J. SHERIFF.
